UNITED STATES PATENT OFFICE

MANUEL A. MONTENEGRO, OF TAMPA, FLORIDA

HEAD REST

Application filed June 16, 1930. Serial No. 461,529.

This invention aims to provide novel means for supporting a person's head, in a vehicle, so that it will be possible for the person to recline and rest or sleep.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:

Figure 1 shows in perspective, a device constructed in accordance with the invention;

Figure 2 is a perspective view showing the device opened, parts being broken away;

Figure 3 is an outside view of the flexible head rest;

Figure 4 is a composite view showing how certain of the suspension members are attached to the head rest;

Figure 5 is a section on the line 5—5 of Figure 2;

Figure 6 is a section on the line 6—6 of Figure 2.

In carrying out the invention, there is provided a flexible head rest 1 which may be made in any desired way, and of any desired materials, such as cloth, leather, imitation leather, and the like. The flexible head rest 1 includes side sections 2 and an intermediate section 3. The head rest, and particularly the side sections 2, may be made as preferred. As shown in Figures 5 and 6, the side sections 2 include an outer body 4 of leather, cloth, or the like, an inner lining 5, which is flexible, like the body 1, and is made of soft material.

A thin padding 6 may be interposed between the lining 5 and the body 4, if preferred.

Near to the forward end of the head rest 1 it is provided with longitudinal openings or slits 10 which renders the portions 36 of the head rest that are immediately adjacent to the slits flexible and yielding, so that the head rest can give somewhat, at the places designated by the numeral 36, to accommodate the ears of the wearer as the head rest 1 bulges outwardly at the ears. The lining 5 may be expanded as shown in Figure 5, at the portions 36 of the head rest to form receptacles 11 for pillows 12 which may be made of feathers or any other sound-deadening material. The flexible head rest 1 fits about the head of the operator as shown in Figure 1 of the drawings, the inner or upper edges of the head rest 1 having notches 7 which expose the temples of the wearer. The head rest 1 is provided in its upper or inner edges with notches 8 located near to the inner end 37 of the head rest, the notches 8 exposing the cheeks of the wearer, coolness being thereby promoted. The top of the head rest may overlap the forehead of the wearer, as shown in Figure 1 at 9.

At the forward upper corners of the head rest 1, there are pockets 14, the constituent walls of which are held together detachably through the instrumentality of snap fasteners 15 or in any other desired way. Headed anchors 16 are secured to the outer walls of the pockets 14.

Loop-shaped connectors 17 are detachably engaged with the anchors 16 and are housed within the pockets 14, so that the connectors will not come into contact with the face of the wearer. Rear suspension members 18, which preferably are elastic, are provided and are formed into adjustable loops 19 engaged through the connectors 17, the loops 19 being held at adjusted lengths through the instrumentality of buckles 20. At their upper ends, the rear suspension members 18 carry eyes 90

21 which are detachably mounted on a hook 22 carried by the roof 23 of the vehicle.

Flexible loops 24 are held through the instrumentality of stitched patches 25 on the 5 forward corners of the head rest 1, near to the upper edge of the head rest. Flexible tongues 26 are engaged through the loops 24 and are held closed by snap fasteners 27 or any other suitable way. The tongues 26 10 are united to loop-shaped connectors 28. Forward suspension members 30 are provided, the forward suspension members 30 being elastic. The forward suspension members 30 are looped at 29 through the connectors 28 and are held at adjusted lengths 15 by buckles 38 or equivalent means. Snaps 31 are mounted on the upper ends of the forward suspension members 30 and are engaged with horizontally spaced hooks 32 on 20 the roof 23 of the vehicle.

The numeral 33 designates a transverse, two-part binder, the constituent members of which may be secured together by snap fasteners 34. At their outer ends, the constituent members of the binder 33 carry rings 35, through which the tongues 26 are detachably engaged.

The device forming the subject matter of this application will be found useful for 30 persons who desire to sleep or rest and relax while travelling or standing still in a vehicle of any kind, such as an automobile, motor bus, truck, aeroplane, sea-plane, dirigible, or the like. The driver may use the device when the vehicle is standing still, and passengers may use it at any time. Persons who are recovering from illness, and are still weak will find comfort in riding, whereas, at present, they are unable to relax in a vehicle. 35 Through the instrumentality of the device forming the subject matter of this application, persons on long trips can relieve one another, and the person who is off duty as a driver can rest himself or relax. The device 40 may be used by hunters, fishermen, and others in the woods, where sleeping places are not available. The device will be found to be comfortable to the operator. It holds the head without objectionable jarring, is not 45 dangerous or uncomfortable, and permits the head to sway a little, if any, turning corners, going around curves, and the like.

The operator, if he wishes, can unsnap the parts of the binder 33 and permit the 50 sides of the flexible head rest 1 to swing outwardly. The device may be made in various sizes, depending upon the size of the head of the person who is using it. The cushions 12 of Figure 5 prevent sound from finding its 55 way into the ears of the user appreciably, and refreshing sleep or quiet is thereby assured. If the operator, wishes, he may dispense with the rear suspension members 18, and they can then be housed in the pockets 60 14. The forward suspension members 30

may be adjusted as to length, owing to the provision of the buckles 38 and the buckles 20 permit an adjustment in the length of the rear suspension members 18. Although the rear suspension members 18 have been shown 70 taut in the drawings, for the sake of simplicity in delineation, they may be left slightly slack, the purpose of the rear suspension members 18 being to limit the side swaying of the head of the user. The relative slant of 75 the suspension members 18 and 30 will depend upon conditions, but they should be adjusted so as to promote comfort, and at the same time hold the head in place. Both the suspension members 18 and 30 preferably have 80 a slight forward inclination, and the suspension members 18 diverge as they extend upwardly. Owing to the relative positions of the hooks 32 and 22, they cause a three-point 85 suspension to be afforded, and the head will be carried in a natural and comfortable manner. The forward suspension members 30 carry the weight of the head, and being elastic they yield and avoid jars, in the event of the vehicle hitting a rough place in the road. 90

All vehicles are not constructed in the same manner, but a skilled mechanic will have no difficulty in mounting the device in the roof or any other accessible part of a vehicle of any kind, regardless of its construction. 95

Having thus described the invention, what is claimed is:

1. A device of the class described, comprising a substantially horizontal, flexible, cap-like head rest open at its inner end, forward suspension members connected at their lower ends to the sides of the head rest and diverging as they extend upwardly, to prevent the inner corners of the head rest from being pulled inwardly against the cheeks of the user, rear suspension members connected at their lower ends to the sides of the head rest and converging as they extend upwardly, to pull in the sides of the head rest, at the outer end thereof, and thereby steady the head of the user, means for anchoring the upper ends of the forward suspension members in spaced relation to each other, and means for mounting the upper ends of the rear suspension members substantially at a common point, thereby to afford a three-point support for the head rest. 105

2. A device of the class described, constructed as set forth in claim 1, and further characterized by the provision of means for adjusting the inner corners of the head rest, to limit the action of the said diverging forward suspension members, said means embodying a releasable binder connecting the sides of the head rest at its forward end. 110

3. A device of the class described, comprising a cap-like head rest having pockets at its sides, suspension members mounted in the pockets, and means for connecting the 115 120 125 130

suspension members to an overhead support, the suspension members being foldable for housing within the pockets.

4. A device of the class described, comprising a flexible, cap-like head rest, means for suspending the head rest from an overhead support, and ear cushions carried by the sides of the head rest, the head rest having slits at the lower ends of the cushions.

10 In testimony that I claim the foregoing as my own, I have hereto affixed my signature.

MANUEL A. MONTENEGRO.
